UNITED STATES PATENT OFFICE.

JACQUES SCHNEIDER, OF SOLOTHURN, ERNST HURLIMANN, OF ZUCHWIL, AND
FREDERIC BILLON, OF SOLOTHURN, SWITZERLAND, ASSIGNORS TO THE FIRM
"SCINTILLA," OF SOLOTHURN, SWITZERLAND.

MAGNETO-ELECTRIC IGNITION MACHINE FOR INTERNAL-COMBUSTION ENGINES.

1,419,767.

Specification of Letters Patent. Patented June 13, 1922.

Application filed August 22, 1919. Serial No. 319,230.

To all whom it may concern:

Be it known that we, JACQUES SCHNEIDER, a citizen of the Swiss Republic, residing at Solothurn, Switzerland, ERNST HURLIMANN, 5 a citizen of the Swiss Republic, residing at Zuchwil, Canton Solothurn, Switzerland, and FREDERIC BILLON, a citizen of the Swiss Republic, residing at Solothurn, Switzerland, have invented certain new and useful 10 Improvements in Magneto-Electric Ignition Machines for Internal-Combustion Engines, of which the following is a specification.

This invention has for its object to provide improved means in magneto electric 15 ignition machines for internal combustion engines, for enabling the entire adjustable interrupter mechanism to be removed from the casing of the ignition machine, for instance for the purpose of inspection, repair 20 or cleaning, and to be replaced ready for use by undoing screws or other separate attachment devices, in a very simple manner, and so that there will be no risk either of the inner parts becoming soiled or of any 25 part becoming loose in working.

According to this present invention the non-rotating part of the interrupter mechanism is mounted in a supporting member which surrounds as far as possible on all 30 sides the cam plate which is mounted on the rotor shaft of the ignition machine for the purpose of operating the interrupter contact. This supporting member is fixed to the machine casing by means of a concentrically 35 rotatable fixing ring which is provided for this purpose with a bayonet fastening that is kept in its closed position by a spring. By overcoming the force of the spring, the 40 fastening can be undone and the interrupter mechanism removed from the machine.

A constructional example of this invention is illustrated in the drawings in which Fig. 1 is a cross section through the axis, of the improved apparatus, and Fig. 2 is 45 a front elevation of the same after removal of the parts *u*, *v* and *y*. The cam plate *b* is mounted on the machine shaft *a*. The ball bearing *c* of the shaft is carried by a nut *d* which can be adjusted axially in the 50 machine casing *e*. In a slightly conical concentric annular groove *f* of this nut there engages coaxially a projecting centring ring *g* of the interrupter-supporting member *h*

in which a bell-crank lever *i* (provided with the rubbing cam part and with the oscillating contact) is mounted on two sides by means of an axle-pin *k*, and the stationary contact *l* is fixed in an insulated manner. 55

In order that there shall be no necessity to undo any contact screw for the purpose 60 of removing the interrupter mechanism, the insulated contact *l* is supplied with current, not by means of a cable, but by means of a spring contact brush *x* that is fixed in an insulated manner to the casing *e*. 65

The supporting member *h* together with all the parts fixed thereon is held by a fixing ring *m* by means of three nibs *n* that are adapted to slide in the annular groove *o* of the machine casing *e*. When it is desired 70 to detach the interrupter mechanism from the casing *e*, the operator rotates a handle *p* of the ring *m* into the mid position (indicated by dot and dash lines), whereby the nibs *n* are brought opposite slots *q* in a rib *r* 75 that covers the groove, so that the entire interrupter mechanism can then be removed in the axial direction from the groove *f* in the bearing nut. In the working of the apparatus the ring *m* is constantly pressed by a 80 spiral spring *s* against a stop *t* of the casing, so that it cannot become undone of itself. In the axial direction it is secured by a cover *u* which is fixed by means of a screw *v* to the interrupter-supporting member, and which 85 also carries the lever *w* for varying the point of ignition, the movement for this latter purpose taking place in the direction of the arrow (Fig. 2) in opposition to the force of the spring *s*. 90

If the apparatus is to be constructed for varying the point of ignition by movement in the opposite direction, it is merely necessary to turn the spring *s* over in such a manner as to cause the interrupter casing *h* 95 together with the lever *w* fixed thereon, to be pressed against a symmetrically situated stop. Consequently the handle *p* of the holding ring *m* will be moved back against a symmetrically situated stop *t'*. 100

As shown, the interrupter mechanism is completely inaccessible in its built-in condition. On removing a protecting cover *y*, only the handle *p* and the interrupter contacts *i*, *l* (not shown in Fig. 2 for the sake 105 of clearness) are exposed and therefore can

be inspected during the working. The other parts are only accessible after the removal of the interrupter mechanism as a whole.

A great advantage of the illustrated construction is afforded further by the double mounting of the interrupter-supporting member *h* which can be rocked by means of the lever *w* for the purpose of varying the point of ignition. This supporting member 10 is mounted not only by means of the centring ring *g* in the bearing nut *d*, but also on the outside of the cam plate *b* in the machine casing *e* by means of an annular projecting rim *z* on the cover *u*.

15 What we claim is:—

1. A magneto electric ignition machine including an adjustable interrupting mechanism on a rockable supporting piece which surrounds an actuating cam as completely as possible on all sides, a fixing ring carrying a cover rotatably mounted on said supporting piece, a spiral spring co-acting with said fixing ring and said rockable supporting piece, tending to rotate said fixing ring 20 and said rockable supporting piece in opposite directions and an abutment on a part of the main casing of the magneto limiting the movement of the said fixing ring and cover.
2. A magneto electric ignition machine including an adjustable interrupting mechanism on a rockable supporting piece which surrounds an actuating cam as completely as possible on all sides, a fixing ring carrying a cover rotatably mounted on said supporting piece, a spiral spring co-acting with said fixing ring and said rockable supporting piece, tending to rotate said fixing ring 25 and said rockable supporting piece in opposite directions, an abutment on a part of the main casing of the magneto limiting the movement of the said fixing ring and cover, means including a bayonet device permitting the removal of the said rockable carrying piece together with the fixing ring and the attached cover from the machine casing when the fixing ring is rotated against the action of the said spiral spring to a position away from contact with the said abutment.

3. A magneto electric ignition machine including an adjustable interrupting mechanism on a rockable supporting piece which surrounds an actuating cam as completely as possible on all sides, a fixing ring carrying a cover rotatably mounted on said supporting piece, a spiral spring co-acting with said fixing ring and said rockable supporting piece, tending to rotate said fixing ring and said rockable supporting piece in opposite directions, an abutment on a part of the main casing of the magneto limiting the movement of the said fixing ring and cover, means including a bayonet device permitting the removal of the said rockable carrying piece together with the fixing ring and the attached cover from the machine casing when the fixing ring is rotated against the action of the said spiral spring to a position away from contact with the said abutment.

3. A magneto electric ignition machine including an adjustable interrupting mechanism on a rockable supporting piece which surrounds an actuating cam as completely as possible on all sides, a fixing ring carrying a cover rotatably mounted on said supporting piece, a spiral spring co-acting with said fixing ring and said rockable supporting piece, tending to rotate said fixing ring and said rockable supporting piece in opposite directions, an abutment on a part of the main casing of the magneto limiting the movement of the said fixing ring and cover, means including a bayonet device permitting the removal of the said rockable carrying piece together with the fixing ring and the attached cover from the machine casing when the fixing ring is rotated against the action of the said spiral spring to a position away from contact with the said abutment, and an extension on said cover for adjustment of the timing of ignition.

In testimony whereof we have signed our names to this specification.

JACQUES SCHNEIDER.
ERNST HURLIMANN.
FREDERIC BILLON.
